UNITED STATES PATENT OFFICE.

JOHN R. LONG, OF AKRON, OHIO.

WRENCH.

No. 890,146.

Specification of Letters Patent.

Patented June 9, 1908.

Application filed February 10, 1908. Serial No. 415,045.

To all whom it may concern:

Be it known that I, JOHN R. LONG, a citizen of the United States, residing at Akron, in the county of Summit and State of Ohio, have invented certain new and useful Improvements in Wrenches; and I do declare that the following is a full, clear, and exact description of the invention, which will enable others skilled in the art to which it applies to make and use the same.

My invention has reference to wrenches, and the invention is an improvement on the wrench patented to me under date of the 17th of April, 1906, and numbered 818,180.

In the accompanying drawings, Figure 1 is a side elevation of the wrench, and Fig. 2 is a cross section on line $x-x$, and Fig. 3 is an edge view of the wrench. Fig. 4 is a perspective view of the inner jaw members, and Fig. 5 is a perspective view of the yoke by which the jaw members are operatively connected.

In the construction of this wrench as compared with the one on which it is an improvement several notable differences occur which materially differentiate the same from the former wrench, as will now appear. Thus, in the present construction I have a handle-bar B provided with an integral jaw 2—2—at its outer end, whereas in my former construction the handle bar has no jaw at all, but had both jaws relatively slidably thereon. The present bar also has two opposite working edges, 3 and 4, the inner of which is straight with the handle of said bar, while outer edge or back 4 is tapered from about the middle of the bar to the outer end thereof and terminating at jaw 2, thus producing a gradual reduction in size or cross section of said bar the entire length of said taper. The handle bar B, therefore, carries the outer jaw 2 as a part thereof, and has a straight inner working edge to which the base of said jaw stands squarely at right angles.

The other or inner jaw member, D, has a jaw 6 at its outer end faced parallel to jaw 2 and with a straight inner edge 7 corresponding to straight edge 3 on the main bar and slidably resting or mounted on said edge, while the outer edge 8 of said member is tapered from the back of its jaw 6 at an angle or degree about twice as great relatively as taper 4 in respect to straight edge 3. This greater taper has several values, but especially enables me to get a long and quick ad-

justment between jaws by a relatively short movement of said member D on the handle-bar, as is obvious, and also promotes both definite locking of the parts and easy release after use.

C represents the yoke or sleeve by which the jaw members or parts B and D are operatively united and utilized. Said yoke or sleeve is formed from tubing cut the desired length and swaged to shape, and is adapted to bear closely against the sides of both members to keep them in working position laterally as well as to serve as a connecting and locking medium for said members, and enlarged or spread at its larger edge or end 10 to adapt it to both engage about the larger areas of that part of the wrench as well as to serve other purposes to be seen, while smaller edge or end 12 presumably retains the original size of the tube from which it was cut. A stop pin d on jaw member D serves to keep the parts operatively together and guiding lugs 20 or their equivalent may be used.

Now, several peculiar and novel features in this wrench over my former wrench are found, first in the broad and conspicuous difference in the location of the jaws, one of said jaws being on the handle-bar and none on the yoke. This relieves the yoke of the direct strain of a jaw and enables me to make a lighter and better wrench. This also throws all the adjustments inward from the outer end of the handle-bar instead of outward beyond the end thereof, as formerly, and which made the smaller member bear the greater strain, preventing such taper being given to the shank of said member D as it now has without weakening it too much for service. Now I can taper to practically a point and promote good service. Again, there is decided improvement in my present construction and arrangement of yoke C in several respects as compared with my former yoke, and the first to be noted is the angle which the yoke sustains in respect to the straight surface 3 of the handle-bar and in respect to which jaws 2 and 6 are arranged. Formerly the yoke was square with the straight edge 3, and in order to get a grip or bite to lock upon the handle-bar a forwardly thrown under lip was required which came in advance of the jaw face on the yoke and on which I depended to lock the parts. Now, I accomplish the same result in a better way

by arranging the yoke at an angle of inclination in respect to straight edge 3, which throws its outer corner 18 forward on bar B and its upper corner 19 rearward on shank D relatively as seen in Fig. 1, and it holds this attitude throughout all adjustments. The degree of said inclination is seen by dotted lines, $y-y$. Furthermore, this not only gives an effectual locking position to the yoke, but by throwing the two jaws together as I do herein independently of the yoke and placing the yoke substantially as shown I am enabled to bring the jaws close together and not make accommodation in the yoke. This enables me to follow the jaws back and forth and to always be sure of a definite locking at any given point and easy unlocking, too, because both the pitch or inclination of the yoke and the pitch of slope on the outer edge of shank D contribute to both results. Again, by this construction the jaws and the handle bar are brought much nearer together and there is not the objection to the wrench tilting or turning in the hand as formerly, when the added thickness of the smaller jaw member was built upon the handle-bar and the jaws were outside of both. Now the work is done directly on the straight edge of the handle-bar and turning of the wrench in the hand is positively avoided. This is a valuable difference made possible only by my new construction.

What I claim is:

1. A wrench comprising a handle-bar having a jaw at its outer end and a tapered working portion next to said jaw, an inner jaw slidably mounted directly upon said bar and having a tapered shank, and a yoke slidably as to both jaws and operatively locking said parts, the said handle-bar and inner jaw and its shank having smooth contact faces, and the said shank having a continuous taper from said inner jaw to its extremity.

2. A wrench having a handle-bar with a jaw on its outer end and the outer edge of said bar tapered toward said jaw, a jaw with a reversely tapered shank mounted on said bar and a slidable yoke uniting said parts.

3. A wrench having a handle-bar with a tapering outer end having a jaw integral therewith, a jaw member slidably mounted on said bar and having a shank of greater taper than said bar extending in the opposite direction to the taper on the bar, and a confining yoke about said parts.

4. A wrench comprising a handle-bar having a tapered outer portion and a jaw rigid with the outer end thereof, a separate jaw member mounted on said bar and having a shank tapering to smaller dimensions from the jaw thereon to its extremity, and a yoke in which both the said handle bar and jaw member are slidably mounted.

5. A wrench having a handle-bar with a tapered outer edge and straight inner edge, a

jaw member having a tapered shank extending rearward from the face of the jaw thereon, and a sleeve slidably connecting said parts across their tapered portions and widest next to said jaws.

6. A wrench comprising a handle-bar with an integral jaw at one end and tapered on its back toward said jaw, an inner jaw mounted on said bar and having a shank tapered oppositely from the taper on said bar, and a yoke uniting said parts having a transverse inclination as to said jaws and bearing its full length on both said tapered surfaces.

7. A wrench having a main bar tapered in its outer portion and a fixed jaw at the extremity of said tapered portion, in combination with an inner jaw having a shank widest next to said jaw and tapering therefrom to its end, and a sleeve slidably engaged over said parts and shaped internally to conform to the taper of both parts.

8. In wrenches, a main bar with a jaw at one end and a handle at the other and tapered on its outer edge toward said jaw, a slidable jaw member mounted on the inner edge of said bar and having a shank with greater taper than said main bar and reversely thereto, and a yoke slidably engaged over said parts and deepest in cross section next to said slidable jaw.

9. A wrench comprising a handle-bar with a jaw on its outer end and having a straight inner edge and a tapered outer edge running to said jaw, a jaw member having a straight edge resting on the straight edge of said handle-bar and a tapered outer edge, in combination with a yoke sleeved to slide as to both said parts and decreasing in cross section internally to make a close engagement on both said jaw member and handle-bar, thereby facilitating locking and unlocking of the parts.

10. A wrench having a handle-bar with a fixed jaw on its outer end and tapered to said jaw in its outer portion, an inner jaw having a tapered shank mounted on said bar and a yoke engaged about both said parts at an inclination to the faces of said jaws and bearing its full length on the said tapered shank and the outer edge of the handle-bar and having both said shank and bar slidable lengthwise therein.

11. A wrench having a handle-bar with a jaw on its outer end and tapered along its outer edge to said jaw, an inner jaw having a shank tapered on its outer edge from the jaw thereon and constructed to engage said handle-bar and keep it in alinement therewith, and a transversely inclined yoke engaged over said shank and handle-bar.

12. A handle-bar having a fixed jaw at its outer end and smooth working edges, and an inner jaw member having a shank with a straight smooth edge resting on said bar and a tapered outer edge, a yoke slidably mount-

ed upon said shank and means to limit the movement of said shank in said yoke.

13. A wrench having a handle-bar with a straight inner edge and a tapered outer edge and a fixed jaw thereon, a jaw member having a shank with a straight inner edge and an outer edge with a greater taper than said handle-bar, a yoke in which both said parts are separately slideable, and means on the end of said shank to confine the same operatively within said yoke.

14. A wrench provided with a handle-bar having a jaw fixed on its outer end and tapered on its outer edge toward said jaw, a jaw member having a shank tapered in reverse direction to the taper on said bar, and a yoke in which both said parts are slideable

independently and the yoke is slideable on both said parts.

15. In wrenches, a handle-bar having an integral jaw and tapered on its outer working edge toward said jaw, a jaw member having a shank tapered reversely to the taper on the said handle-bar and to a greater degree, and a yoke slideable on the tapered edges of both 25 said parts, thereby locking the parts together with a frictional wedging effect.

In testimony whereof I sign this specification in the presence of two witnesses.

JOHN R. LONG.
